UNITED STATES PATENT OFFICE.

COLIN D. BARRETT, OF PROVIDENCE, RHODE ISLAND, ASSIGNOR TO FARBER BROTHERS, OF NEW YORK, N. Y., A COPARTNERSHIP CONSISTING OF LOUIS FARBER AND HARRY FARBER.

DESIGN FOR A METAL BORDER STRIP OR SIMILAR ARTICLE.

Application filed April 4, 1923. Serial No. 5,695. Term of patent 7 years.

To all whom it may concern:

Be it known that I, COLIN D. BARRETT, a citizen of the United States, and a resident of Providence, in the county of Providence and State of Rhode Island, have invented and produced a certain new, original, and ornamental Design for Metal Border Strip or Similar Article, of which the following is a specification, reference being had to the accompanying drawings, forming part thereof.

The figure is a representation of a strip or panel illustrating my new design, being shown in two views, one being a continuation of the other.

My border strip is a separate article of manufacture intended to be applied to tableware in general.

I claim:

The ornamental design for a metal border strip or similar article, as shown.

COLIN D. BARRETT.
